DESIGN FOR A COMBINED AIR CONDITIONING UNIT AND DISPLAY CABINET

Frank Chalmers, York, Pa.

Application November 3, 1944, Serial No. 116,119

Term of patent 14 years

(Cl. D80—11)

To all whom it may concern:

Be it known that I, Frank Chalmers, a citizen of the United States of America, residing at York, in the county of York and the Commonwealth of Pennsylvania, have invented a new, original, and ornamental Design for a Combined Air Conditioning Unit and Display Cabinet, of which the following is a specification, reference being had to the accompanying drawings, forming part thereof wherein

Fig. 1 is a perspective view of a combined air

conditioning unit and display cabinet embodying my new design;

Fig. 2 is a front elevational view of the same;
Fig. 3 is a side elevational view of the same;
and

Fig. 4 is a top plan view of the same.

I claim:

The ornamental design for a combined air conditioning unit and display cabinet, as shown.

FRANK CHALMERS.
